Primary Examiner—Bruce W. Dunkins*Assistant Examiner*—Martha Thompson*Attorney, Agent, or Firm*—Christie, Parker & Hale**[57]****CLAIM**

The ornamental design for a ball-point pen, as shown and described.

DESCRIPTION

FIG. 1 is a right side elevational view of a ball-point pen showing my new design with the writing tip in a retracted position, the left side being a mirror image thereof;

FIG. 2 is a front elevational view;

FIG. 3 is a rear elevational view;

FIG. 4 is a left side elevational view with the writing tip in an extended position, the right side being a mirror image thereof;

FIG. 5 is a bottom plan view; and

FIG. 6 is a top plan view thereof.
